UNITED STATES PATENT OFFICE

110,200

DESIGN FOR A MERCHANTISE DISPLAY RACK

Frederick A. Sunderhauf, Rutherford, N. J., assignor to Reynolds Metals Company, Richmond, Va., a corporation of Delaware

Application April 22, 1938, Serial No. 76,697

Term of patent 7 years

To all whom it may concern:

Be it known that I, Frederick A. Sunderhauf, a citizen of the United States, residing at Rutherford, in the county of Bergen and State of New Jersey, have invented a new, original, and ornamental Design for a Merchandise Display Rack, of which the following is a specification, reference being had to the accompanying drawing forming a part thereof, wherein:

The figure illustrates a perspective view of a merchandise display rack showing my design.

I claim:

The ornamental design for a merchandise display rack, as shown.

FREDERICK A. SUNDERHAUF.
